Inc., St. Louis, Mo., a corporation of
Missouri

Application July 29, 1944, Serial No. 114,620

Term of patent 14 years

(Cl. D48—23)

To all whom it may concern:

Be it known that we, David J. Biller and Bertram A. Kaeppel, citizens of the United States and residents of the city of St. Louis and State of Missouri, and of Normandy, in the county of St. Louis and State of Missouri, respectively, have invented a new, original, and ornamental Design for a Louvered Fluorescent Lighting Fixture, of which the following is a specification, reference being had to the accompanying drawing, forming part thereof.

Fig. 1 is a perspective view of a louvered fluo-

rescent lighting fixture, showing our new design;
and

Fig. 2 is a vertical transverse sectional view thereof.

The side and end not shown in Fig. 1 are the same, respectively, as the side and end appearing therein.

We claim:

The ornamental design for a louvered fluorescent lighting fixture, as shown and described.

DAVID J. BILLER.
